UNITED STATES PATENT OFFICE.

ARCHIBALD J. TURNER, OF CHICAGO, ILLINOIS, ASSIGNOR TO WILSON-WESTERN SPORTING GOODS COMPANY, OF CHICAGO, ILLINOIS, A CORPORATION OF DELAWARE.

INFLATABLE BALL.

Original application filed April 20, 1925, Serial No. 24,337. Divided and this application filed May 27, 1926. Serial No. 111,911.

My invention relates to inflatable balls and is concerned with the provision of improvements relating to the bladder insertion opening of such a ball and to the means for closing such opening.

This application is a division of my co-pending application, Serial No. 24,337, filed April 20, 1925.

The improvements which characterize the invention herein described and subsequently claimed are admirably adapted for use in an inflatable ball which includes a bladder provided with a valve stem supported by and in the cover in such a way that the ball may be inflated after the bladder insertion opening is closed.

Generally speaking, the present invention provides an inflatable ball provided with a bladder insertion opening closing means, which is so constructed that such closing means is or may be practically invisible when the ball is inflated and ready for play.

In the accompanying drawings,

Figure 1 is an elevational view of a basketball embodying the improvements of my invention;

Figure 2 is an enlarged fragmentary sectional view taken on the line 2-2 of Fig. 1;

Figure 3 is an enlarged fragmentary interior view of the parts of the ball with which my invention is particularly concerned; and

Figure 4 is an isolated sectional view of the resilient member which, in a preferred embodiment of the invention, supports and cushions the valve stem of the bladder.

Referring first to Figs. 1 to 3, I have illustrated a basketball comprising the usual cover consisting of the several leather members 10-10 which are stitched together in the usual or any suitable manner. For a short distance, approximately three or four inches, the contiguous margins of a pair of the cover members are left unstitched to provide the bladder insertion opening 11. Disposed adjacent each of the margins of the opening 11 and secured to the inner surfaces of the contiguous cover members 10

are the opening reinforcement strips 12 and 13 each of which comprises a leather strip 50 folded back upon itself along its central longitudinal line and disposed adjacent the inner surface of the associated cover member 10 with the folded margin of said strip presented to the opening 11. Strips 12 and 55 13 are secured to their associated cover members by stitching 14, 15 and 16. Stitchings 14 and 15 pass through the cover members 10 and through both plies of the reinforcing strips 12 or 13, while stitching 16 60 merely extends through the cover members and through the outer plies of the reinforcing strips 12 and 13. This construction provides elongated lace-receiving pockets 17 and 18 which are provided with spaced 65 apertures at the folds of the strips 12 and 13, these apertures being designated 17^a, 17^b, 17^c, etc., and 18^a, 18^b, 18^c, etc. Adapted to cooperate with the said apertures and the pockets 17 and 18 is a lace 19. The manner 70 in which this lace is passed through the said apertures and pockets will be herein-after described in detail.

Disposed within the aforesaid cover is a rubber bladder 20 provided with a hollow 75 metal valve stem 21 through which it may be inflated. This valve stem is mounted on the bladder in substantially the same way that an automobile tire stem is mounted on its 80 associated inner tube. Valve stem 21 is relatively short, is provided with external threads 22 and is equipped with the usual or any suitable "valve insides", which, of course, comprises a valve seating against 85 pressure from the outside and comprising the usual valve unseating member 23.

Formed in one of the cover members 10 and located adjacent the bladder insertion opening 11 is a circular aperture 24 which 90 registers with corresponding apertures in both plies of the adjacent reinforcing strip 12, these several apertures, on account of the three thicknesses of leather through which they extend, affording a passage through 95 the cover which is of a length considerably

greater than the distance from the top of the valve stem 21 to the top of the valve unseating member 23.

Disposed adjacent the inner ply of the reinforcing strip 12 is the stem holding and cushioning member which is illustrated in detail in Fig. 4. This member, as illustrated in the accompanying drawings, consists of a rectangular piece of comparatively soft rubber 25 which is molded around an internally threaded sleeve 26 which, in turn, is provided with a flange 27 whereby it is securely anchored in said rubber cushion 25. Element 25 is preferably reenforced by a piece of fabric 28 which is embedded therein and which extends from sleeve 26 to the margins of the cushioning element. The cushioning element is preferably provided with a plane surface 29 to engage the reenforcing strip 12 and with a convex curved surface 30 for engagement with the bladder. Member 26 is preferably thick at its central portion and thins out toward its edges. Attention is directed to the fact that both the sleeve 26 and its flange 27 lie within the plane surface 29 so that any sharp blow against the cover in the vicinity of the said sleeve will be cushioned from such sleeve (and from the bladder valve stem) by the intervening rubber.

The aforesaid valve stem holding and cushioning member is attached to the reenforcing strip 12 with the sleeve 26 in registry with the passage through the cover, the rubber element 25 being stitched in position and also, if desired, having its surface 29 cemented to the inner ply of the reenforcing strip 12. As a means for holding the cushioning element in position, I may use the stitching 14 and 15 which also holds the reenforcing strip 12 in position, or I may use separate stitching extending along the longitudinal margins of the rubber element and extending through the adjacent leather. Stitching also may be extended along the end margins of the cushioning element. In any event, the stitching by which the cushioning element is held in position should lie a sufficient distance away from the margins of the sleeve flange 27 to permit the necessary yielding of the sleeve 25 and the valve stem when the ball is in play. These distances need not be great, but should exist.

Let it be assumed that the bladder 20 is out of the cover and that the lace 19 is also removed from the cover. In preparing the ball for play, the deflated bladder 20 is inserted through the cover opening 11 and the external threads of the valve stem 21 are turned into cooperating engagement with the internal threads of the sleeve 26 of the cushioning element. With the parts 21 and 26 thus properly assembled, the upper end of the valve stem lies in the passage through the leather cover, but lies well within the

outer surface of the cover. It is thus free from contact with the hands of a player or other object the ball may engage, but is so located that a tire pump may be applied to the stem. The valve stem will usually be provided with internal threads to engage suitable external threads on the coupling member which forms part of the pump.

The lace 19 is now applied, its ends being inserted into the pockets 17 and 18 through the apertures 17^a and 18^a, respectively, and being led through such pockets and out of the apertures 17^b and 18^b, respectively. The end of the lace thus extended out of the aperture 17^b is then led through the aperture 18^b and along the pocket 18 to the aperture 17^c, where it emerges from the pocket 17 and again enters the pocket 18 through the aperture 18^c. The portion of the lace which emerged from the pocket 17 through the opening 17^b similarly enters the pocket 18 through aperture 18^b, leaves said last mentioned pocket through aperture 18^c and enters pocket 17 through aperture 17^c. This manner of threading the two portions of the lace through the pockets and pocket apertures is continued across the opening, the two ends of the lace being tied securely together at the left side of the opening (Fig. 3), the knot and the superfluous ends of the lace being tucked down to lie within the cover.

The type of lacing just described is very effective and desirable in connection with a basketball. It draws the opposed edges of the opening 11 tightly together in such a way that the ball is practically as smooth over the opening as it would be if the opening did not exist. Furthermore, no part of the lacing is exposed to view or for contact with the fingers of a player. Moreover, the lacing is so well protected by the reenforcing strips 12 and 13 that it has practically no tendency to chafe the bladder.

After the ball has been laced up as just described, a suitable pump is applied to inflate the bladder. Whenever the ball becomes soft it may again be inflated by the application of the pump to the bladder valve stem.

Having thus illustrated and described a preferred embodiment of my invention, what I claim is new and desire to secure by Letters Patent of the United States is—

In an inflatable ball of the class described, a bladder and a cover, a valve stem for said bladder, an elongated slit in said cover for the insertion of said bladder, means spaced from said slit for supporting said valve stem and for providing access thereto from the exterior of the cover when said slit is closed, reenforcing strips associated with said slit, each of said reenforcing strips being folded upon itself and being secured to one of the margins of the insertion opening with its

folded edge presented to the slit, said reenforcing strips affording pockets through which a lace may be extended in lines parallel to the slit, a plurality of pairs of oppositely located apertures formed in the folded edges of said reenforcing strips, and a lace passing across said slit on the inside of the

cover and being passed parallel to the slit through said pockets, substantially as described and illustrated. 10

In witness whereof, I hereunto subscribe my name this 24th day of May, 1926.

ARCHIBALD J. TURNER.
